UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

WATERPROOF ELECTRIC FITTING.

Application filed October 18, 1918. Serial No. 259,745.

To all whom it may concern:

Be it known that I, REUBEN B. BENJAMIN, a citizen of the United States, residing at Chicago, in the county of Cook and State of Illinois, have invented new and useful Improvements in Waterproof Electric Fittings, of which the following is a full, clear, concise, and exact description, reference being had to the accompanying drawing, forming a part of this specification.

The present invention relates generally to water-proof electric fittings which are adapted for use in the open where they will be subjected to all kinds of weather conditions or for use in places where subjected to the action of vapors or fumes from water, oil or other chemical substances. The invention is concerned more particularly with a fitting of this general class which is adapted for the connection of an electric lamp and in which the lamp is protected by a globe which is secured to the fitting.

The principal object of the invention is to provide a fitting of this particular type which will prove water-tight under all conditions of use and particularly so in case the globe is broken and the fitting left exposed in this condition. In my device the water-proof joints are all maintained independently of the globe and consequently the breaking of the latter or its entire removal will not lessen the efficiency of the device as a water-proof fitting. Another object of the invention is to provide a construction in which all the parts may be readily assembled and adjusted. In one respect this result is obtained by closing one side of the box of the fitting, by a flexible water-proof gasket and allowing the socket contacts to extend through an opening in this gasket. These and other objects, features and advantages of my invention will be more fully understood upon referring to the following detailed description taken in connection with the accompanying drawing, and the scope of the invention will be particularly pointed out in the appended claims.

In said drawing,

Fig. 1 is a side elevation of a fitting constructed in accordance with my invention, parts being broken away and parts shown in a central vertical section;

Fig. 2 is a horizontal sectional view taken

on a plane indicated by the line 2-2 of Fig. 1;

Fig. 3 is a vertical section of the socket member and connecting gasket taken on a plane indicated by the line 3-3 of Fig. 2; and

Fig. 4 is a detail vertical section taken on a plane indicated by the line 4-4 of Fig. 2. Throughout these views, like characters refer to like parts.

Referring to the drawing in detail, 10 designates a box or housing for enclosing the wiring leading to the terminals on the socket base 11 which constitutes a wiring base and contact support. This box in the present instance is a bulk-head fitting provided at one side with a flange 12 by which it may be secured to a bulk-head or other suitable support and at the other side with a flange 13 to which the globe-retaining member or ring 14 is connected. The latter connection may be made in any desired way as for example by the screws 15 passing through openings in the ring 14 into engagement with threaded openings in the flange 13. In the present instance, the box 10 is provided with a lug 16 and a bridging member 17 which serve as supports for the base 11 of the electric socket member. The base 11 is provided with laterally extending portions 12 which are notched for the reception of retaining screws 18 which pass into threaded openings in the lug 16 and member 17. The base 11 may be readily detached by simply loosening the screws 18 and slightly rotating the base so as to free it from the screws. By tightening the screws 18 the base will be securely held in place.

The base 12 is provided with a center contact 19 and an outer shell contact 20. These are the usual contacts for connection to the terminals of an incandescent lamp such as the lamp 21. The center contact is yielding at its contacting end as clearly illustrated. At its non-contacting end it is rigidly held by a retaining screw 22 which passes through openings in terminal plate 23, base 11 and contact 19. A nut 24 securely holds the parts together. The terminal plate 23 is provided with an up-turned lug 25 and a co-operating binding screw 26. This screw engages a threaded opening in the plate 23 and passes into a recess or open-

ing in the base 11. The shell contact 20 is provided with a flange 27 which extends around a considerable portion of its circumference and serves to form a bearing 5 for engagement with the face of the base 11. Its flange is provided with three openings for the passage of the retaining screws 28. These screws pass through openings in the base 11 and at least one of them extends 10 through an opening in a terminal plate 29 which is provided with a lug 30 and binding screw 31 which are similar to the terminal connections associated with the center contact 19. The circuit is completed through 15 the lamp by way of terminal plate 23, screw 22 and center contact 19 to one lamp terminal and by way of terminal plate 29, screw 28 and shell contact 20 to the other lamp terminal. The shell contact 20 is formed so as 20 to provide an inner and outer thread. The inner thread is for engagement with the correspondingly threaded lamp terminal and the outer thread is for engagement with the clamping ring or member 32.

25 The box 10 with its terminal connections is rendered water-tight by means of a gasket 33 which is perforated at its center for the passage of the contacts of the socket member. The perforation is such as to just pass 30 the shell contact 20. The inner periphery of the gasket, formed by this aperture, is securely clamped in place by the member 32 being screwed upon the shell 20. The end of the member 32 forms an engaging face 35 which cooperates with a similar engaging face upon the base 11 to tightly hold the gasket 33 in place and with sufficient pressure to maintain a water-proof connection. The outer periphery of the gasket 33 lies 40 between the flange 13 of the box 10 and the globe-retaining member 14. These two parts are, as above noted, secured together by the screws 15. The gasket 33 is thus secured at its outer periphery with a water-tight connection. The fact that the gasket 33 is 45 flexible allows a certain amount of play for the ready assembling of the parts. The gasket will also take up any slight inequalities in the engaging faces of the base 11 and 50 members 16 and 17 which might arise in the course of manufacture.

The interior of the globe-retaining ring 55 14 is provided with a thread which cooperates with the exterior thread formed upon the open end of the globe 34. This globe is of sufficient size to enclose a lamp 21 and when screwed home bears against the gasket 33. In case the globe 34 should be broken to such an extent as to cause its threaded 60 end to be disengaged from the ring 14 or in case the globe should be entirely removed, then the water-tight joint at the outer periphery of the gasket 33 would not be impaired but would remain the same as when 65 the globe was in place.

The globe 34 is protected by a guard formed by the rods 35 which are secured to a ring 36. This ring is provided with an interior thread which cooperates with a thread upon the exterior of the globe-retaining member 14, thus providing a compact and neat construction for the protecting 70 guard.

In practice the conductors will be led through a suitable conduit into the box 10 75 where they will be connected to the terminals of the socket member by means of the binding screws 26 and 31. In order to place the lamp 21 in position it will obviously be necessary to remove the ring 36 and the globe 34. At such time, as well as in case of the accidental breaking of the globe the interior of the box 10 will be thoroughly 80 protected from the weather or injurious effects such as might arise by the presence of 85 objectionable gases, fumes or vapors.

What I claim as new and desire to secure by Letters Patent of the United States, is:

1. A water-proof electric fitting comprising a box having an open side, an electric 90 socket base secured within said box and extending in the direction of said open side, suitable socket contacts on said base, a clamping member adjustably secured to said base, a globe-retaining member secured to 95 said box about its open side, and a water-proof gasket secured at its outer periphery between said globe-retaining member and said box and at its inner periphery between 100 said clamping member and said base.

2. A water-proof electric fitting comprising a box having an open side, an electric socket base secured within said box and extending approximately to the plane of its open side, shell and center contacts secured 105 to said base, terminal connections for said contacts on said base, a clamping ring screwed on to the exterior of the shell contact, said ring having a clamping face cooperating with a like face on said base, a globe-retaining member secured to said box about its open side, and a water-proof gasket secured at its outer periphery between said 110 globe-retaining member and said box and at its inner periphery between the clamping 115 faces on said clamping ring and base.

3. A water-proof electric fitting comprising a wiring base provided with wiring terminals, a housing for said wiring base having an opening through which said wiring base is inserted into position, means for mounting said wiring base in fixed position in said housing, the edges of said opening being spaced a substantial distance from 120 said wiring base, a gasket closing the space between the edges of said opening and said wiring base, means for clamping said gasket against the edge of said opening, means for clamping said gasket against said wiring 125 base, and receptacle contacts mounted on 130

5 said wiring base, said gasket being of yieldable, flexible material and mounted for flexible movement, whereby it may be flexed to accommodate itself to the position of the 6 wiring base in the housing.

4. A water-proof electric fitting comprising a wiring base provided with wiring terminals, a housing for said wiring base having an opening through which said wiring base is inserted into position, means for mounting said wiring base in fixed position in said housing, the edges of said opening being spaced a substantial distance from said wiring base, a gasket closing the space 10 between the edges of said opening and said wiring base, means for clamping said gasket against the edge of said opening, means for clamping said gasket against said wiring base, and receptacle contacts mounted on 15 said wiring base, said gasket being of yieldable, flexible material and mounted for flexible movement, whereby it may be flexed to accommodate itself to the position of the wiring base in the housing, said receptacle contact being mounted substantially outside 20 said housing.

5. A water-proof electric fitting comprising a wiring base provided with wiring terminals, a housing for said wiring base having an opening through which said wiring base is inserted into position, means for mounting said wiring base in fixed position in said housing, the edges of said opening being spaced a substantial distance from 25 said wiring base, a gasket closing the space between the edges of said opening and said wiring base, means for clamping said gasket against the edge of said opening, means for clamping said gasket against said wiring 30 base, and receptacle contacts mounted on said wiring base, said gasket being of yieldable, flexible material and mounted for flexible movement, whereby it may be flexed to accommodate itself to the position of the wiring 35 base in the housing, and a globe for surrounding the lamp bulb in the socket.

6. A water-proof electric fitting comprising a wiring base provided with wiring terminals, a housing for said wiring base having an opening through which said wiring base is inserted into position, means for mounting said wiring base in fixed position in said housing, the edges of said opening being spaced a substantial distance from said wiring 40 base, a gasket closing the space between the edges of said opening and said wiring base, means for clamping said gasket against the edge of said opening, means for clamping said gasket against said wiring base, and receptacle contacts mounted on said wiring base, said gasket being of yieldable, flexible material and mounted for flexible movement, whereby it may be flexed to accommodate 45 itself to the position of the wiring base in the housing, said receptacle contact being

mounted substantially outside said housing, the edges of said globe being seated on said gasket adjacent the edges of said opening.

7. A water-proof electric fitting comprising a wiring base provided with wiring terminals, a housing for said wiring base having an opening through which said wiring base is inserted into position in said housing, means for mounting said wiring base in said housing, lamp contacts mounted 70 on said wiring base, a globe for enclosing the lamp in said lamp-socket, a gasket adjacent the edges of said opening, and a clamping ring for clamping said gasket against said housing, said clamping ring 75 and globe being provided with inter-engaging means whereby said globe may be detachably secured to said clamping ring and whereby said clamping ring will hold said gasket tight even when the said globe is 80 broken or removed.

8. A water-proof electric fitting comprising a wiring base provided with wiring terminals, a housing for said wiring base having an opening through which said wiring base is inserted into position in said housing, means for mounting said wiring base in said housing, lamp contacts mounted on said wiring base, a globe for enclosing the lamp in said lamp-socket, a gasket adjacent the 85 edges of said opening, and a clamping ring for clamping said gasket against said housing, said clamping ring and globe being provided with inter-engaging means 90 whereby said globe may be detachably secured to said clamping ring, and whereby said clamping ring will hold said gasket tight even when the said globe is broken or removed, the inner edge of said globe being 95 in sealing engagement with said gasket. 100

9. A water-proof electric fitting comprising an insulating base provided with wiring terminals, a housing for said base having an opening through which said base is inserted into position, means for mounting said base in fixed position in said housing, the edges of said opening being placed a substantial distance from said base, a gasket closing the space between the edges of said opening and said base, means for clamping said gasket against the edges of said opening, a threaded shell contact mounted on said base substantially outside said housing, and means for clamping said gasket against 110 said base comprising a sleeve threaded on the outside of said threaded shell contact, said gasket being of yieldable, flexible material and mounted for flexible movement 115 whereby it may be flexed to accommodate itself to the position of the wiring base in the 120 housing.

In witness whereof, I have hereunto subscribed my name.

REUBEN B. BENJAMIN.
